M. HASTINGS.

PLUMB, LEVEL, DEGREE FINDER, AND SURVEYOR'S INSTRUMENT.

APPLICATION FILED AUG. 28, 1908.

919,860.

Patented Apr. 27, 1909.

UNITED STATES PATENT OFFICE.

MAYME HASTINGS, OF FRESNO, CALIFORNIA.

PLUMB, LEVEL, DEGREE-FINDER, AND SURVEYOR'S INSTRUMENT.

No. 919,860

Specification of Letters Patent.

Patented April 27, 1909.

Application filed August 22, 1908. Serial No. 450,689.

To all whom it may concern:

Be it known that I, MAYME HASTINGS, a citizen of the United States, residing at Fresno, in the county of Fresno and State of California, have invented new and useful Improvements in Plumbs, Levels, Degree-Finders, and Surveyors' Instruments, of which the following is a specification.

This invention relates to an instrument designed for use by mechanics, builders and the like, whereby building or boundary lines can be easily and conveniently obtained and which can be used as a level, plumb, rule and as a degree finder.

15 The invention has for one of its objects to provide an instrument of the character referred to which is compact and practically formed and readily manipulated and reliable in use.

20 Another object of the invention is the provision of an instrument having two dials or hands for obtaining horizontal, perpendicular or other lines accurately and quickly, the observations being made by either dial and hand, the instrument also being provided with sight devices and a compass.

With these objects in view and others, as will appear as the description proceeds, the invention comprises the various novel features of construction and arrangement of parts which will be more fully described hereinafter and set forth with particularity in the appended claims.

In the accompanying drawing, which 35 illustrates one of the embodiments of the invention:—Figure 1 is a perspective view of the instrument with the sight devices in place for use in surveying. Fig. 2 is a plan view of the central portion of the instrument, showing the compass. Fig. 3 is a sectional view of the end of the instrument, showing the pocket for holding the sight devices. Fig. 4 is a central vertical transversé section showing the dials and index hands.

45 Similar reference characters are employed to designate corresponding figures in the several views.

Referring to the drawing, A designates the body of the instrument which is in the form 50 of a straight bar flat on all sides. In the center of the body is a transverse opening 1 formed with annular shoulders or seats 2 against which are positioned the dials 3 which are provided with degree marks. Sup- 55 ported on both dials is a central arbor 4, the ends of which project beyond the dials and

carrying hands 5 that are each weighted at one end so as to always maintain a perpendicular position. Over the hands are glass or transparent plates 6 spaced from the 60 hands and dials by rings 7. Disposed over both sides of the body A at the central portion thereof are metal plates 8 having openings 9 of less diameter than the glass plates 6 so as to engage the portions of the latter to 65 retain them in place, the retaining plates being provided with flanges 10 extending over the top and bottom of the body A for firmly securing the retaining plates in position. By means of either dial and hand, horizontal, 70 perpendicular or inclined lines can be accurately determined by the relation of the hand with the degree marks. The end corners of the body A when the latter is made of wood or the like are protected by metal pieces 11 as 75 shown in Figs. 1 and 3.

In order to adapt the instrument for use in surveying a pair of sight devices B are employed each being mounted on a stem 12 that screws into threaded sockets 13 in the top of 80 the body A adjacent the ends thereof, there being a collar 14 on the stem that bears on the top face of the body 8 to hold the sight device stationary. When not in use these devices are stored in a chamber 15 in one end 85 of the body A which chamber is normally closed by a door or slide 16. In the top flanges 10 of the retaining plates 8 is formed an opening 17 that registers with and displays a compass 18 set into the body A and 90 when not in use, this compass is protected by a cover 19. This compass is employed for determining the angles between building or boundary lines in the surveying operation.

From the foregoing description, taken in 95 connection with the accompanying drawing, the advantages of the construction and of the method of operation will be readily apparent to those skilled in the art to which the invention appertains and while I have described 100 the principle of operation of the invention, together with the device which I now consider to be the best embodiment thereof, I desire to have it understood that the device shown is merely illustrative and that such 105 changes may be made when desired as are within the scope of the claims appended hereto.

I claim:—

1. An instrument of the class described 110 comprising a stock having an opening extending from one side to the other, dials se-

cured in the openings and having central apertures, an arbor mounted in the apertures, weighted hands secured to the extremities of the arbors and rotatable over the dials, 5 transparent cover plates disposed in the openings, and a metal housing extending entirely around the stock to form a retaining means for the cover plates, said housing having openings in its side through which the 10 hands and dials are exposed, and means for securing the housing in place on the stock.

2. An instrument of the class described comprising a stock having an opening, shoulders in the opening, dials disposed in the 15 opening and bearing on the shoulders, spacing devices bearing on the outer faces of the dials and extending around the marginal portion thereof, transparent cover plates disposed in the opening and bearing against the 20 spacing devices, and a metal housing extending around the stock to form a retaining means for the cover plates and dials, said

housing consisting of side plates having openings through which the dials and hands are exposed and having portions extending 25 over the top and bottom of the stock, and fastenings extending through the parts of the housing for securing the same to the stock.

3. An instrument of the class described comprising a stock provided with an opening, 30 a plumb and level device in the opening, cover plates for the opening, a housing extending around the stock and constituting a retainer for the cover plates, said housing having an opening in its top, a compass set 35 into the stock and exposed through the top opening of the housing, and a cover attached to the housing for protecting the compass.

In testimony whereof I affix my signature in presence of two witnesses.

MAYME HASTINGS.

Witnesses:

MARGARET S. HASTINGS,
JAMES HASTINGS.
